UNITED STATES PATENT OFFICE.

CHARLES A. GLOEKLER, OF PITTSBURG, PENNSYLVANIA.

SMOKE-HOUSE.

SPECIFICATION forming part of Letters Patent No. 629,351, dated July 25, 1899.

Application filed February 23, 1898. Serial No. 706,516. (No model.)

To all whom it may concern:

Be it known that I, CHARLES A. GLOEKLER, a citizen of the United States, residing at Pittsburg, in the county of Allegheny and State of Pennsylvania, have invented new and useful Improvements in Smoke-Houses, of which the following is a specification.

My invention relates to houses for smoking butchers' products, and has for one of its objects to provide a smoke-house embodying a knockdown casing and a rotary support for the products to be smoked readily detachable from its base and also from the knockdown casing.

Another object of the invention is to provide a smoke-house embracing a rotatable support for the products to be smoked and means for imparting an intermittent rotary motion to said support while the smoke-house is in use, whereby all of the products in the house are subjected to the action of the same or substantially the same amount of smoke, and uniformity in the color of the products is insured.

With the foregoing ends in view the invention will be fully understood from the following description and claims when taken in conjunction with the accompanying drawings, in which—

Figure 1 is a perspective view of my improved smoke-house as it appears when ready for use. Fig. 2 is a vertical section of the same on an enlarged scale. Fig. 3 is a horizontal section taken on the line 3 3 of Fig. 2. Fig. 4 is an enlarged perspective view of the support for the products to be smoked, the same being shown as removed from the house.

In the said drawings similar letters designate corresponding parts in all of the several views.

The casing A of my improved smoke-house is preferably built of sheet metal and is of octagonal form in cross-section. It is made up of a top wall or roof a of octagonal form, two side sections b, having flanges c at one vertical edge, two side sections d, having flanges c at their opposite vertical edges, flat side sections e e', interposed between the two sections d and between the sections d b, respectively, and detachably connected by bolts f to the flanges of the same and a side section g, which is connected by hinges to one sec-

tion b, so as to serve as a door, and is preferably provided with a latch h, designed to engage a keeper i on the other section b. At 55 their lower ends the side sections b d e e' are detachably connected by bolts f' to the vertically-disposed portion of an octagonal angle-iron base j, and at their upper ends said side sections are detachably connected by bolts 60 f'' to the vertically-disposed portion of an octagonal angle-iron k, which in turn is permanently connected to the top wall or roof a. By reason of the construction described when it is desired to ship the smoke-house from one 65 point to another the side sections b d e e' of the casing A may be readily disconnected from each other and from the base-iron j and the top or roof a by simply removing the connecting-bolts f, f', and f'', and may be conveniently packed, so as to take up but a minimum amount of room in shipment. It also follows from the construction described that when the parts of the casing A arrive at the point where the smoke-house is to be located 75 said casing parts may be connected together quite as readily as they were disconnected.

In the door-section g of the casing A, at a point adjacent to the lower end thereof, are formed a sufficient number of draft-openings 80 g' to support combustion of the smoke-making fuel in the casing, and in the top wall a of said casing and preferably at an opposite point with respect to the openings g' is a smoke-eduction aperture a'. Arranged on the 85 ground or other support on which the casing A rests and located in the center of said casing is a pedestal B. This pedestal is provided in its upper end with a bearing l, in which is journaled the lower trunnion m of the support C for the products to be smoked, the upper trunnion n of which extends through and is journaled in the top a of the casing and a reinforcing-plate p thereon. The support is preferably in the form of a reel and comprises 95 a lower head q, an upper head r, angle-iron uprights s, connecting the lower and upper heads, and angle-iron bars t, connecting the uprights at either side of the reel and having outwardly-directed lateral arms u. The angle-iron bars t are designed to support removable bars, on which sausages and other products to be smoked are placed, after the manner shown in Fig. 4, and the lateral arms u

of said bars *t* are also designed to support sausages and other products.

As best shown in Fig. 2, the trunnion *n* of the reel or product-support *C* extends above the roof of the casing *A*, where it is provided with a wheel *D*, bearing upwardly-directed teeth *v*. These teeth of the wheel *D* are designed to be engaged by the tappet *w* of a wheel *E*, which is fixed on a shaft *F*, journaled in suitable bearings on the casing *A*, and hence it will be seen that when the smoke-house is in use and the shaft *F* is rotated an intermittent rotary motion will be imparted to the reel or product-support *C*—that is to say, said reel or support will be caused to make a portion of a revolution incident to each complete revolution of the wheel *E* and shaft *F*. By virtue of this the products to be smoked are left in one position but a short time, and consequently all the products will be smoked to the same extent and all will be of the same color. This is also true when the fire is built adjacent to the door *g* or at one side of the smoke-house, for it will be observed that all of the products will be presented to such side in succession.

The intermittent rotation of the reel or product-support *C* is also advantageous, because it enables an operator standing at the door-opening of the casing and without said casing to remove all of the smoked products from the reel or support and charge said reel or support with fresh products while the smoke-house is in operation. This discharging and charging of the reel or support *C* is also materially facilitated by the use of the bars of wood or other material which rest on the angle-bars *t*, since said wood bars with their loads of sausages or other products may be very readily placed on and removed from the reel or support *C*.

For the purpose of permitting a ready disconnection of the casing *A* from the reel or product-support *C* when the casing is to be knocked down for shipment the upper trunnion *n* of the reel is not connected to the upper head *r* of the reel, but is simply keyed in said head after the manner shown in Fig. 2. From this it follows that not only may the casing be readily disconnected from the reel when the casing is to be knocked down, but

said casing may be as readily connected to the reel when its parts are again assembled and connected together.

I prefer to employ the angle-iron base *j* at the lower end of the casing *A*, since it lends strength and stability to said casing. I do not desire, however, to be understood as confining myself to the use of the base *j*, as the casing is complete without the same. I also do not desire to be understood as confining myself to the specific construction and relative arrangement of the parts as herein shown and described, as such changes or modifications may be made in practice as fairly fall within the scope of my invention.

Having thus described my invention, what I claim is—

1. In a smoke-house, the combination of a casing having a door in its side wall and also having an inlet for air and an outlet for smoke located at opposite points, a rotary support arranged in the casing and having a trunnion journaled in the top thereof, a shaft journaled in bearings on the casing and adapted to be continuously rotated by a suitable motor, and intermittent gearing between said shaft and the trunnion of the product-support for partially rotating the support incident to each rotation of the shaft, substantially as specified.

2. In a smoke-house, the combination of a knockdown casing having a door, a pedestal loosely arranged in said casing, a rotary product-support having a trunnion journaled in and removable from the pedestal, a trunnion keyed in and removable from the upper end of said support and journaled in the top of the casing, the wheel *D* fixed on the latter trunnion above the casing and having teeth *v*, and the shaft journaled in bearings on the top of the casing and having the wheel *E* provided with a tappet arranged to engage the teeth of the wheel *D*, substantially as specified.

In testimony whereof I have hereunto set my hand in presence of two subscribing witnesses.

CHARLES A. GLOEKLER.
